UNITED STATES PATENT OFFICE.

JULIUS LEEDE, OF WASHINGTON, DISTRICT OF COLUMBIA, ASSIGNOR OF ONE-HALF TO GRANVILLE H. OURY, OF FLORENCE, ARIZONA TERRITORY.

PROCESS OF MIXING AND CONSUMING HYDROCARBON WITH PULVERIZED EARTH.

SPECIFICATION forming part of Letters Patent No. 292,236, dated January 22, 1884.

Application filed August 30, 1883. (No model.)

To all whom it may concern:

Be it known that I, JULIUS LEEDE, residing at Washington, District of Columbia, have invented certain new and useful Improvements 5 in Process of Mixing Hydrocarbons with Fine Earthy Matter and of Consuming the Same; and I do hereby declare the following to be a full, clear, and exact description of the invention, such as will enable others skilled in the 10 art to which it appertains to make and use the same.

My invention relates to a process of mixing hydrocarbons with fine earthy materials or with granulated coal, sawdust, or other like 15 granular or powdered material for fuel, and to a process of mixing and simultaneously consuming such mixed or compound fuel; and my invention consists, essentially, first, in mechanically feeding a stream of granular material and a stream of liquid carbonaceous material in juxtaposition and by a powerful blast scattering both streams and mixing the materials of both.

My invention consists, secondly, in the process of mixing, as above referred to, in a furnace and simultaneously igniting and consuming the carbon of the mixed fuel.

In carrying out my invention I construct an apparatus consisting of a hopper for holding 30 the granular or powdered material provided with suitable conveyers and conduits for conducting the material to the mouth of the furnace; a suitable tank for holding the hydrocarbon provided with pipes, cocks, &c., for 35 conducting and regulating the flow thereof under a head or under a pressure to the mouth of the furnace; a suitable blower and a system of pipes or means for creating a blast to scatter or diffuse both the liquid and solid materials, and thereby causing a perfect admixture of the two, and a gas or other flame arranged near the mouth of the conduits of solid and liquid materials and of the blast-pipes, whereby the mixed fuel is ignited. This process 40 may be advantageous in metallurgical processes in this, that the fluxes may be mixed and projected into the furnace by this process, furnishing a vehicle for separating the liquid carbon as well as a flux or medium to assist in 45 the fusion and reduction of metals.

A convenient form of apparatus for carry-

ing out my process of mixing and consuming hydrocarbons and a base is shown in the drawing, in which the figure is a side elevation, showing the earth-conduit, the hydrocarbon-conduit, the blast-pipe, gas-pipe, blower, and hopper. 55

In the drawing, A is a Root or other blower mounted upon a suitable base. Upon the blower is mounted by frame-work a system of 60 gearing and a separate conduit, similar to those shown and described in my application for apparatus for feeding and consuming pulverized fuel, filed of even date herewith.

B is the air-trunk, from which spring blast 65 tubes or pipes b b, which are connected with the trunk by dovetail bases b'.

C is a pipe leading from a tank of petroleum or other hydrocarbon, the nozzle of which dips, as shown. 70

D is the pulverized earth-conduit leading from the hopper E to the furnace. The conveyer is provided near its extremity with a series of mouths or openings, d', through which the pulverized earthy material drops by gravity until caught and dispersed by the blast. The conveyer d is driven through suitable 75 gearing driven from the main blower-shaft.

F is a conduit leading from the furnace, which has a hopper-like bottom, to the hopper E. 80 Within this conduit there is a conveyer driven by suitable gearing, which transfers the fine earthy matter which falls to the bottom of the furnace to the hopper E, to be used over and over again. 85

In carrying out my process it will be observed that any suitable means of feeding the pulverized earth or of feeding the hydrocarbon may be adopted, as well as any suitable means for producing a blast or a flame, the essential characteristics of my invention being, first, bringing the two kinds of material in juxtaposition, and then scattering by a blast, and thereby mixing them; and, second, in simultaneously igniting by any means the carbon so mixed, so as to utilize the separation of the carbon and the supply of oxygen due to the blast in the consumption of the carbon. 90

Having thus fully described my invention, what I claim as new, and desire to secure by 95 Letters Patent, is—

1. The process of mixing fine material and

liquid carbon for the production of fuel, consisting in conducting a stream of fine material and a stream of hydrocarbon and discharging said materials from their conduits in juxtaposition, and while suspended intermixing the particles of both streams by a separate stream or blast of air, as hereinbefore set forth.

2. The process herein described of mixing fine material and liquid carbon, and simultaneously igniting and consuming the carbon, consisting in conducting a stream of fine material and a stream of hydrocarbon, and discharging said materials from their conduits in juxtaposition, and while suspended intermixing the particles of both streams by a separate stream or blast of air, and simultaneously

igniting the fuel by a jet-flame, as hereinbefore set forth.

3. In an apparatus for mixing earthy matter and hydrocarbons, and for consuming the carbon therein, the combination of means for feeding the earthy matter, a separate conduit for the liquid carbon, means for producing and separately conducting a blast, and jet for ignition, substantially as set forth.

In testimony whereof I affix my signature in presence of two witnesses.

JULIUS LEEDE.
